US0D1005769S

(12) **United States Design Patent** (10) Patent No.: **US D1,005,769 S**
 Bahreinian et al. (45) Date of Patent: ** Nov. 28, 2023

(54) OVEN	5,365,833 A	11/1994	Chen
(71) Applicant: NewAge Products Inc. , Toronto (CA)	5,413,033 A	5/1995	Riccio
	5,492,055 A	2/1996	Nevin et al.
	5,605,092 A	2/1997	Riccio
	5,620,623 A	4/1997	Baker
	5,823,174 A	10/1998	Andress
	5,928,540 A	7/1999	Antoine et al.
	6,000,388 A	12/1999	Andress
	6,037,569 A	3/2000	Lincoln et al.
	6,038,964 A	3/2000	Sikes
	6,041,769 A	3/2000	Llodra, Jr. et al.
	6,050,177 A	4/2000	Lassig, Jr.
	6,073,623 A	6/2000	Maschhoff
	6,082,352 A	7/2000	Hsu
	6,093,918 A	7/2000	Sohn
	6,098,613 A	8/2000	Wiersma
	6,143,341 A	11/2000	Sikes
	6,153,858 A	11/2000	Barnes et al.
